UNITED STATES PATENT OFFICE.

CHARLES S. HOLDEN, OF WORCESTER, MASSACHUSETTS, ASSIGNOR, BY MESNE ASSIGNMENTS, TO HOLDEN KNITTING CO., OF WORCESTER, MASSACHUSETTS, A CORPORATION OF MASSACHUSETTS.

KNITTED ARTICLE AND METHOD OF MAKING SAME.

Application filed August 25, 1921. Serial No. 495,156.

To all whom it may concern:

Be it known that I, CHARLES S. HOLDEN, a citizen of the United States, residing at Worcester, in the county of Worcester and Commonwealth of Massachusetts, have invented a new and useful Improvement in a Knitted Article and Method of Making Same, of which the following, together with the accompanying drawings, is a specification.

My invention relates generally to articles of knitted material and has for its object to provide, as an improved article of manufacture, a knitted article which may be readily drawn over the hand and which may then be employed, in somewhat the same manner as a sponge or mop, for purposes of washing when in a wet condition or for polishing when in a dry condition.

My invention further contemplates an improved method of manufacture whereby knitted articles of the above described nature may be cheaply and easily made from material formed by knitting machines of the type commonly used for the manufacture of hosiery and other knitted articles generally tubular in form. These and other advantageous features of my invention will hereinafter more fully appear reference being had to the accompanying drawings in which,

Fig. 1 is a plan view of a portion of a continuous web of knitted material from which my improved articles of manufacture are to be made.

Fig. 2 is a view of a length of material cut from the web shown in Fig. 1 from which a single article is to be made.

Fig. 3 is a view of the length of knitted material shown in Fig. 2 following the carrying out of several steps in my improved method of manufacture.

Fig. 4 is a view showing a completed article applied to the hand of a user.

Referring to Fig. 1, a web of material, generally tubular in form, is produced by any suitable knitting machine with certain portions 1 thereof more closely knit than other portions 2 thereof. The portions 2, therefore, appear wider than the portions 1 and the operation of the machine is so regulated that the portions 1 and 2 are formed alternately, the portions 2 being of greater length than the portions 1. Obviously the

relative width and length of the portions 1 and 2 can be readily controlled, as desired, as is well known to those skilled in the art of knitting.

A continuous web of material knitted, as shown in Fig. 1, having been produced, separate lengths of material are taken therefrom by cutting every other closely knitted portion 1 along the dotted lines, so that each severed length of material appears as shown in Fig. 2. The next step in the manufacture of my improved article is to slip an annular band 3 of resilient material over one of the portions 2 and positioning it at substantially the middle of the closely knit portion 1. The band 3 may be composed of any suitable inherently resilient material, such as rubber, and tends to gather the knitted material together at substantially the middle of the portion 1. The band 3 is then held by hand, or any other suitable means, in the position shown in Fig. 2 while one-half of the severed length of material is pulled over the other half as shown in Fig. 3 until the ends of the half portions 1^a and 1^b are even with each other. The article then has the appearance shown in Fig. 4, in which the band 3 will be entirely concealed and will tend to draw the portion 1 together to the extent that this end of the article will be considerably narrower than the other end of the article.

The half portions 1^a and 1^b are then sewed together as indicated at 4 and, if desired, the ends of the half portions 1^a and 1^b may be trimmed to give a finished appearance. Stitches indicated at 5 may also be taken through the folded-over portion 1 in order to confine the band 3 in the position shown. The completed article is then ready to be drawn over the hand of the user, as shown in Fig. 4, from which it is apparent that the hand of the user will be completely enclosed by the article and will be prevented from slipping off the hand by the fact that the band 3 tends to hold the folded-over portion 1 in close contact with the wrist of the user. It is obvious that the folded-over portions 2 are of ample width and length to allow the hand to remain in the article without being cramped.

The article may then be used as a sponge or mop for the purpose of scrubbing or washing and it is obvious that it is adapted for

a wide variety of usages. For instance, it is particularly adapted for washing automobiles as it can hold as much water and soap as an ordinary sponge and, unlike a sponge, can be applied to all parts of an automobile or other similar vehicle without having to hold it. Furthermore, it can be applied to places which cannot be reached by an ordinary sponge, such as in between the spokes of the wheels, and in between the many rods and other members encountered in the under bodies of automobiles. Obviously my improved article may be as readily employed when washing or scrubbing surfaces located in other inconvenient places. A further advantage of my article lies in the fact that one article can be applied to each hand of the user without materially affecting the use of the hands when the user desires to employ them to hold or steady himself. This is impossible when using an ordinary sponge or mop, and it will be readily seen that a window washer equipped with two of my improved hand mops will be able to use first one hand and then the other for either washing the window or supporting himself.

A still further advantage of my improved article lies in the fact that the user may employ the article on one hand for washing and the article on the other hand for polishing the surface which has been washed. As a further aid to the user when it is desired to employ the article as a polishing means, a piece 6 of polishing material, such as chamois, may be secured to the inside of one of the portions 2, before the article is completed as indicated in Fig. 2. The piece 6 will then be disposed inside of the article after it is completed, but can be readily

made accessible for use by turning the article inside-out. Obviously other modifications of this sort can be made for adapting the article for special uses, such as for instance as sewing a piece of material impregnated with some polishing or abrasive compound to the portions 2, in somewhat the same manner as shown in Fig. 2.

While I have shown my invention as being carried out for the production of articles shaped as shown in the drawings and have described its use in detail for certain purposes, it is obvious that the article may have other forms and may be used for other purposes without departing from the spirit and scope of my invention. I desire therefore that only such limitations be imposed thereon as may come within the scope of the appended claim.

I claim,

The method of making improved knitted articles for cleaning purposes, which consists in first providing a length of tubular knitted web comprising a series of portions of equal lengths and diameters separated by a series of portions of smaller lengths and diameters and being more closely knit, any two of the longer portions and any two of the smaller portions being exactly similar, then cutting said tubular knitted web at every other smaller portion, passing rubber bands around the intermediate smaller portions, then pulling one long portion of each piece so cut over the band and over the other long portion, until the severed ends meet, and finally securing the ends, thus forming articles providing a tube having unbroken double walls, one end thereof being closed.

CHARLES S. HOLDEN.
